UNITED STATES PATENT OFFICE.

THOMAS DARK, OF BUFFALO, NEW YORK.

DEVICE FOR CLEANING STREET SEWER-PIPES.

SPECIFICATION forming part of Letters Patent No. 309,696, dated December 23, 1884.

Application filed July 7, 1884. (No model.)

To all whom it may concern:

Be it known that I, THOMAS DARK, a citizen of the United States, residing at Buffalo, in the county of Erie and State of New York, 5 have invented certain new and useful Improvements in Devices for Cleaning Street Sewer-Pipes and Sewers, of which the following is a specification, reference being had therein to the accompanying drawings.

10 This application relates to improvements on my patent of August 10, 1880, No. 231,015, for "devices for cleaning out street sewer-pipes and sewers;" and the present improvements relate more particularly to the man-

15 holes in the streets and their covers, all as fully hereinafter explained.

In the drawings, Figure 1 is a longitudinal section divided in the middle, showing the sewer, the street-openings thereto, the devices for cleaning, &c.; Fig. 2, a top plan showing the oval man-hole opening into sewer; Fig. 3, a top plan of oval metal rim to man-hole; Fig. 4, a top plan of cover for same; and Figs. 5 and 6, cross-sections of cover, showing the under braces.

A A represent the vertical openings into the sewer S, with its catch-basins B beneath. The mouth or man-hole A' to these openings is on a level with the street, and has a cast-30 iron frame of oval form set therein corresponding to the form of the opening A'. It is made oval for the reason that the ordinary round man-hole would be too small to set the leg C of my cleaning device in and allow a man therein to work at the same time, and if made larger and round it would take too 35 much room in the street. By making it oblong or oval plenty of room for the working of the device is got and the man-hole only a 40 little enlarged one way—viz., in length. This oval opening is surrounded by a metal rim, R, and which projects into the ground a short distance, ending in a flange, R', which rests on the brick walls of the man-hole, on which 45 sets the pavement, which will come flush with the top of the rim. Inside, and a little below the outer rim, is another rim, r, forming a seat for the cover T to set on, the seat having inside projecting lugs, s s, (see Fig. 3,) to 50 give additional surface for the cover to rest

on and insure stability. The cover is of iron, and is strengthened by cross-braces, t t, cast on the under side, as in Figs. 5 and 6, and in dotted lines, Fig. 4. These are mainly to prevent the cover springing out when unevenly stepped on by a horse, the ends of the braces t projecting down below the seat r and setting close to the wall of the rim, as in Figs. 5 and 6. In addition, headed pins or lug projections u u on the sides or edge of the 60 cover are made, which set into corresponding slots or depressions, w w, in the upper rim, R. These all make the cover immovable except by a straight upward pull, and will prevent rattling and danger of coming off to the 65 injury of horses' legs, &c. The oblong shape of the cover is important, as it cannot be jumped out by any peculiar pressure on its edges, as round ones are liable to be. These 70 oval openings will usually be about two feet wide by three feet long; and in cleaning sewers and sewer-pipe by my devices previously patented the winch or windlass will set over it, yet giving plenty of room for working the chain E from the windlass over the sheave k 75 and through the sewer, making a connection from one windlass to the other, as explained in my patent previously mentioned.

Attached to the chain E are the cup-plow g, then a connecting-rod, e, (instead of a chain, 80 as in the previous patent,) fastened to the back of the plow by a rule-joint, and at its other end by a similar joint to an open-mouthed scraper, f. The stiff rod e and joints are important to keep the scrapers in proper 85 position and guide them, and also prevent their turning or twisting, and to especially prevent their catching on the curved edges of sewers and getting fast.

I claim—

1. In combination with the vertical openings A A in streets, and which lead to the sewer or sewer-pipe, the oval-shaped man-holes A', having the metal rim R and flange R', seat r, lugs s s, and cover T, all arranged 95 substantially as and for the purpose specified.
2. The combination of the street-openings A A, oval man-hole A', metal flanged rim R R', the rim R having slots w w therein, and the cover T, provided with projecting headed 100

lugs u to set therein, all substantially as and for the purpose specified.

3. In combination with the oval man-hole A and metal rim R R' r, the cover T, provided with the under cross-braces, t t, the ends projecting downward and coming close to the inside wall of rim R, as and for the purpose specified.

In testimony whereof I affix my signature in presence of two witnesses.

THOMAS DARK.
